UNITED STATES PATENT OFFICE

1,997,936

REFRIGERATOR CONTAINER

William F. Kiesel, Jr., Hollidaysburg, Pa., assignor to The Pennsylvania Railroad Company, Philadelphia, Pa., a corporation of Pennsylvania

Application October 10, 1932, Serial No. 636,968

3 Claims. (Cl. 62—91.5)

My invention relates to refrigerator containers wherein solid carbon dioxide or a like refrigerant, that is, one which changes directly from a solid state to a vapor, is used as the refrigerant medium. While especially applicable to railway shipping containers, the invention may be used to advantage as applied to many other types of containers ranging from small boxes to refrigerator cars, and to stationary as well as movable refrigerator units.

The object of my invention, generally stated, is to provide a simple and inexpensively constructed container, satisfying certain requirements which are peculiar to refrigeration by carbon dioxide, and to provide means for controlling, according to the use for which the container is designed, the refrigerating effect. To this end the container of my invention is characterized by a number of separate compartments, one for accommodating the lading to be refrigerated, one for accommodating the solid refrigerant and isolating the gas generated by it from the lading space, and a third or intermediate compartment, conveniently referred to as a "cold air receptacle", so designed as to control the circulation of air within the lading space and thus regulate the rate of sublimation in the refrigerant bunker, and give the desired refrigerating effect in the lading space.

Other objects and advantages characterizing my invention will become more fully apparent from the description of one embodiment or example of my invention which follows herein-after, having reference to the accompanying drawings. Of the drawings:

Fig. I represents a plan view of a refrigerator container of my invention with a portion thereof shown in horizontal cross section.

Fig. II represents a longitudinal vertical cross section of the same, taken as indicated by the lines II—II of Fig. III; and,

Fig. III represents a transverse vertical cross section of the same, taken as indicated by the lines III—III of Fig. II.

In the drawings, there is shown a container which, in its exterior dimensions and form, corresponds closely to merchandise containers such as are transported on railway cars, trucks, or the like, and are generally arranged end to end in a single row, occupying the full platform space of the vehicle. The container is provided with the usual lifting hooks 1 by which it may be connected to a hoist for the purpose of shifting it from car to truck, from car to stationary platform, or vice versa.

The container comprises generally an outer metal casing 2, an inner metal shell 3 and a lining 4 of insulating material therebetween. The outer casing 2 is so made and fitted at the joints as to render it substantially air-tight and sturdy enough to withstand the rough usage to which containers are subjected in service. The base of the container is preferably supported on a rectangular framework of channel bars 6. Extending longitudinally along the top of the container there is a hatch 7, normally closed by a cover 8 and rendered gas-tight by a plug 9, through which the refrigerant medium may be charged into the container.

While the particular form of insulation for the lining 4 between the outer casing 2 and the inner shell 3 admits of considerable variation, I prefer to employ a material known commercially as "dry zero" for the sides, ends and roof of the container, as well as for the body of the hatch plug 9. At the base of the container, as indicated at 10, I prefer to employ celotex or balsa wood. At each side of the container, in the center thereof, double doors 11 are provided, the doors being divided horizontally. The doors 11 are carefully fitted and sealed at their edges in the manner of refrigerator doors, and they are divided into separate sections so that only one section need be opened at a time when access to a part of the container is desired.

Beneath the filling hatch 7 there is a bunker 12 adapted for the accommodation of cakes of solid carbon dioxide, the bunker having a base portion 13 in the form of a metal tray suspended from the roof of the container. The refrigerant bunker 12 is of a size such as to occupy nearly the full area of the lading space at the top thereof. The space within the refrigerant bunker is completely enclosed, except for a vent 14, shown in Fig. III, through which carbon dioxide gas generated in the bunker may escape to the atmosphere, and is isolated from the lading space of the container. Preferably the tray 13 is made of aluminum or other metal of good heat conducting quality.

Suspended from the roof of the container beneath the bunker 12 there is a box-shaped partition 15 which is disposed horizontally and spaced from the bottom of the tray 13 to afford a narrow passage 16 for the circulation of air. The partition 15 has therein a series of perforations 17. At its outside edge there is a solid upturned flange 18 substantially surrounding the base of the bunker. Between the flange 18 and the inner shell 3 at the roof of the container there

is a narrow intake passage 19 through which air is admitted to the space above the partition 15. The box-shaped partition 15 is made of porous insulating material, such as balsa wood, and 5 serves to define a receptacle through which cold air may filter to the lading space beneath it.

In operation, the circulation of gas in the above described container is as follows. Relatively warm air surrounding the lading and rising to the 10 top of the container passes upward along the side and end walls of the container and enters the narrow intake passage 19 from whence it flows into the passage 16 between the tray 13 and the partition 15. Sublimation of the solid carbon 15 dioxide in the bunker 12 generates carbon dioxide gas which fills the interior space of the bunker, excess pressure being relieved by the vent 14. Through the medium of the heat conducting metal of the tray 13, heat is absorbed from the air 20 therebeneath. Incident to the chilling of the air in the passage 16, condensation may result from the contact of the relatively warm air with the cold metal tray 13, and the moisture may be deposited on and absorbed to some extent by the 25 porous partition 15. From the passage 16, air flows slowly through the perforations 17 and commingles with the warmer air below. Moreover, the moisture absorbed by the partition 15 is gradually given up to the relatively dry air below the 30 partition 15 where such conditioning is especially required.

By having the upturned flanges 18 disposed near the side and end walls and extending upward nearly to the roof of the container, the relatively warm air rising to the top of the container will attain some velocity as it flows into the cold air receptacle, there to be cooled by contact with the metal base 13 of the refrigerant bunker. The partition 15 is essentially of foraminous material, that is, it may be simply porous with capacity to absorb and transmit to the space below a well disseminated amount of cold air, or it 35 may have perforations distributed over its area, or it may be both porous and perforated. The amount of cold air which will pass from the cold 40 air receptacle to the lading space below over a certain time can be regulated by the porosity of the material and the size and number of the perforations. Moreover, the characteristics of the cold air receptacle may obviously be varied by 45 closing part or all of the perforations in the partition 15 according to the use to which the container is to be subjected.

The circulation of air within the container will 50 vary according to the difference in temperature between the air at the top and bottom, but this circulation may be modified or controlled by proportionment of the size of the passages leading to the cold air receptacle. The circulation of air as described above is clearly indicated by the 55 arrows in Figs. II and III.

While I have described one particular form or example which my invention may take, it will be

apparent to those skilled in the art that various changes may be made in the form and arrangement of the parts of the container, without departing from the spirit of my invention as defined in the claims hereto annexed.

5

Having thus described my invention, I claim:

1. In a refrigerator container, a casing lined with insulating material, a bunker extending across said casing beneath the top thereof, said bunker affording a support for solid carbon dioxide or a like refrigerant, and isolating the refrigerant space from the remaining space within the casing, and a box-shaped foraminous flow-restricting partition suspended at the top of the casing at a spaced distance beneath said bunker 10 and forming therewith a relatively narrow and unobstructed passage for the circulation of air, the perforations of said foraminous partition being relatively small and numerous and distributed substantially over a horizontal cross section of 15 the container, whereby said partition serves to control percolation of a well disseminated body of air from the space above it to the space below it.

2. In a refrigerator container, a casing lined 20 with insulating material, a hatch at the top of said casing, a bunker extending across said casing beneath said hatch, said bunker affording a support for solid carbon dioxide or a like refrigerant, and isolating the refrigerant space from 25 the remaining space within the casing, and a perforated flow-restricting partition of porous material disposed horizontally beneath said bunker above the lading space of the casing and spaced from the bunker to afford a narrow and 30 unobstructed passage for the circulation of air, the perforations of said partition being relatively 35 small and numerous and distributed over substantially the entire lading space whereby said partition serves to control percolation of a well 40 disseminated body of air from the space above it to the space below it.

3. In a refrigerator container, a casing lined 45 with insulating material, a hatch at the top of said casing, a bunker extending across said casing beneath said hatch and occupying substantially the full area at the top of the lading space 50 of the container, said bunker affording a support for solid carbon dioxide or a like refrigerant, and isolating the refrigerant space from the remaining space within the casing, and a foraminous flow-restricting partition disposed horizontally beneath said bunker and spaced uniformly 55 therefrom, said partition including imperforate upturned flanges substantially surrounding the base of the bunker, the perforations of said foraminous partition being comparatively small and distributed over substantially the entire area 60 of the container whereby said partition serves to control the percolation of a well disseminated body of air from the space above it to the space below it.

WILLIAM F. KIESEL, JR.
